US0D1032894S

(12) **United States Design Patent** (10) **Patent No.:** **US D1,032,894 S**
(45) **Date of Patent:** **** Jun. 25, 2024**

(54) **LED HEADLIGHT BULB**

(71) Applicant: **Haomian Zheng**, Guangdong (CN)

(72) Inventor: **Haomian Zheng**, Guangdong (CN)

(73) Assignee: **Shenzhen Aosituo Technology Co., Ltd.**, Shenzhen (CN)

(**) Term: **15 Years**

(21) Appl. No.: **29/858,384**

(22) Filed: **Oct. 31, 2022**

(51) LOC (14) Cl. **26-06**

(52) U.S. Cl.

USPC **D26/28; D26/2**

(58) **Field of Classification Search**

USPC **D26/2, 24, 28-36, 138, 139**

CPC **F21K 9/00; F21K 9/20; F21K 9/23; F21K 9/232; F21W 2103/00; F21W 2103/30; F21W 2103/35; F21W 2103/40; F21W 2103/55**

CLAIM

The ornamental design for a LED headlight bulb, as shown and described.

DESCRIPTION

FIG. 1 is a front elevational view thereof;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of a LED headlight bulb showing my new design; and,

FIG. 8 is a perspective view of a LED headlight bulb showing my new design.

The broken lines in the drawings illustrate portions of the LED headlight bulb that form no part of the claimed design.

1 Claim, 7 Drawing Sheets
